UNITED STATES PATENT OFFICE.

GERRITT SMITH, OF ASTORIA, NEW YORK.

QUADRUPLEX TELEGRAPH.

SPECIFICATION forming part of Letters Patent No. 291,236, dated January 1, 1884.

Application filed May 22, 1883. (No model.)

To all whom it may concern:

Be it known that I, GERRITT SMITH, a citizen of the United States, residing in Astoria, in the county of Queens and State of New York, have invented certain new and useful Improvements in Diplex or Quadruplex Telegraphs, of which the following is a specification.

The object of my invention is to provide an improved receiving system, whereby two separate messages or series of signals simultaneously transmitted from one station over a single electrical conductor may be received at a second station without interference; and it consists in a novel arrangement of receiving apparatus at one station, in combination with a main battery in two sections and two transmitting-instruments at a second station, capable of directing upon the line a current of two different strengths and varying polarity.

The receiving system in general use at the present time, in connection with a transmitting system of the nature indicated, consists of two separate and locally-independent relays, one polarized and responding only to reversals, the second neutral and responding only to changes in current strength; and it has been found that when, in the course of transmission, a reversal in the polarity of the main-line current takes place while a strength of current is upon the line for influencing the neutral relay, there will be a short interval, during which a cessation of magnetism in the neutral cores will occur, and the armature of the neutral relay will tend to fall back, thus causing a false signal.

My present arrangement of receiving apparatus is not subject to this difficulty, and while it is adapted to receive and register two separate series of signals, it may be advantageously employed to replace the neutral relay, when such relay is used, as above described, and to receive one series of signals only, in connection with a separate and locally-independent polarized relay for receiving a second series of signals, thus obviating the difficulty referred to. My invention is also capable, when used in connection with any of the well-known forms of duplex telegraphy, of transmitting and receiving

direction—simultaneously upon a single electrical conductor.

In Letters Patent of the United States No. 189,276, dated April 3, 1877, I have described a transmitting system wherein two transmitters capable of independent action are so arranged with reference to each other and to a main battery or batteries that their separate and combined action may produce four distinct electrical conditions in the main line, differing from each other in respect to the strength or polarity of the current, or both; and I have selected this arrangement of the transmitting system for illustrating my present invention.

My arrangement of receiving apparatus, which I term a "compound relay," consists in combining two electro-magnets and an armature for each in such relative positions that the respective armatures, each influenced and controlled by an adjustable retractile spring and appropriately situated contact-stops, under certain conditions of the main-line current will mechanically connect and co-operate to influence local circuits containing two receiving-sounders, the said armatures thus, with reference to each other and the aforesaid contact-stops, assuming four different positions corresponding to the four possible positions of the transmitters at the distant station.

Figure 1 is a plan view of my compound relay, showing the two receiving-sounders and their electrical connections with suitably-arranged transmitting-instruments. Figs. 2, 3, and 4 show the position of the receiving apparatus corresponding to the different positions of the accompanying transmitters, and Fig. 5 shows my compound relay in connection with a modification of the transmitting system.

My compound relay is composed of two electro-magnets, R R', situated, respectively, upon the ends S of permanently-magnetized steel bars N S, upon the opposite end, N, of which the armatures r r' are pivoted, the arrangement of both magnets so far being substantially the same as that of the well-known magnet used in Siemens's polarized relay. Each armature is controlled by adjustable spiral retracting-springs s s', of substantially equal power, the retractile force of either of which is only overcome by the greater strength of

current. The armatures are capable of a lateral movement, r' , being limited by the insulated stops c and d , while r is limited in one direction by the insulated stop e , and in the other by the electrical contact-stop f . The outer ends of both armatures are provided with suitable contact-points, a and b , and move in the same horizontal and vertical plane. Under the influence of the greater strength of current of either polarity the armatures assume an extreme position and are separated. When the weaker strength of current is upon the line, one armature or the other, according to the polarity of such current, assumes an extreme position, aided by its retracting-spring; the other armature takes a position nearly central, thus establishing electrical contact between the ends of the two armatures; but if, while the weaker strength of battery is upon the line and the armatures are in the position last described, a reversal of the main-line current occurs, the two armatures, while maintaining electrical contact between themselves, will move to the opposite side, and the local circuit established by such contact between the two armatures will be uninterrupted.

The two receiving-sounders S and S' and their local circuits are connected to the compound relay as follows: S is connected with contact-point f , the circuit extending through the coils of sounder S , local battery $L B$, wire 20, 22, to the armature r , the circuit being completed at points $f f'$. S' is connected to armature r' by wire 19, the circuit passing through coils of S' , local battery $L B'$, wire 20 and 22, to the armature r' , circuit being completed through contact-points a and b .

It will be seen by inspection that as both electro-magnets R and R' have the same polarity, the main line $M L$ is passed through them in opposite directions, so that a current of any given polarity will cause the armatures to move in the same direction, their relative position being reversed. The same object would of course be attained by polarizing the electro-magnets with opposite polarities and passing the main line through them in the same direction. In Fig. 1 the transmitters K and K' are both open and a current of $+\frac{1}{2} B$ is to line. Armatures r and r' , in response to the greater strength of positive current, are carried to their extreme positions into contact with the limiting stops c and c' , respectively, and both local circuits are open. In Fig. 2 transmitter K is closed and K' is open. A current of $-4 B$ is to line. In response to a reversal of the greater strength of current, armature r' is carried to its opposite extreme position against the limiting-stop d . Armature r is also carried to its extreme position, and electrical contact is made between points f and f' , whereby the local circuit of sounder S is completed through elements f , S , $L B$, 21, 22, r , and f' , whereupon sounder S responds. In Fig. 3 transmitter K' is closed and K is open. A current of $+\frac{1}{2} B$ flows to

line, and armature r' , by reason of the decreased strength of current, aided by retracting spring s' , assumes an extreme position against limiting-stop c . Armature r , acting against the force of spring s , assumes a nearly central position, and connection between the ends a and b of armatures r and r' is effected, whereby the local circuit of sounder S' is completed through the elements a , r' , 19, S' , $L B'$, 20, 22, r , and b , and sounder S' responds. In Fig. 4 K and K' are both closed. A current of $-B$ flows to line. Armature r , by reason of the reversal in polarity of current and aided by retracting-spring s , assumes an extreme position against electrical contact-stop f , and the circuit of sounder S is completed at $f f'$. Armature r' , acting against the force of retracting-spring s' , assumes a nearly central position, and contact between a and b is made, thus closing the circuit of sounder S' , whereby both sounders respond. It will thus be seen that sounder S responds solely to the operation of transmitter K , and that sounder S' responds only to the operation of transmitter K' .

It is to be observed that if, while the apparatus is in the position shown in Fig. 3, transmitter K be closed and the apparatus assume the position shown in Fig. 4, no break in the electrical connection between points a and b will occur, and the signal in process of reception on sounder S' will be uninterrupted.

Fig. 5 is a modification of the arrangement of transmitters, also shown in the aforesaid United States Letters Patent No. 189,276, in which the different electrical conditions of the main line occur as follows: With K and K' open there is a current from $+\frac{1}{2} B$; K closed and K' open, a current from $-3 B$; K' closed, K open, no current; K and K' both closed, a current from $-B$.

The operation of the receiving-instrument and its local connections is in each instance substantially like that described above, except that spring s' of the armature r' should be given a resiliency sufficient to overcome spring s of armature r .

In another application I have described and claimed a receiving system composed of the herein-described form of compound relay in combination with a second polarized relay for receiving two simultaneous transmissions, as above referred to.

The apparatus herein described may be combined with well-known means for duplex transmission and two series of signals in opposite directions, four in all, may thus be transmitted and received.

I do not abandon or dedicate to the public any patentable features set forth herein and not hereinafter claimed, but reserve the right to claim the same by any reissue hereof, or by any subsequent application.

What I claim, and desire to secure by Letters Patent, is—

1. In a diplex telegraph, means for transmitting two strengths of current and for re-

versing either strength of current, in combination with a main line, a relay having two armatures adapted to come in contact with each other to form an electrical connection, a stationary electrical contact for one of said armatures, and two local sounders, one of said sounders being operated upon contact of the two armatures, and the other upon contact between one of said armatures and its stationary electrical contact.

2. In a diplex telegraph, the combination of means for transmitting two strengths of current and for reversing either strength of current, a main telegraph-line, an electro-magnetic receiving-instrument having two polar magnets, two armatures adapted to come in contact, a stationary electrical connection to form contact with one of said armatures, and two local sounders, one of said sounders being operated by connection of the two armatures, and the other upon contact of one of the armatures and its stationary electrical contact.

3. In a diplex telegraph, the combination of

means for transmitting two strengths of current and for reversing either strength of current, a main line, a relay having two polar electro-magnets, and two respective armatures capable of establishing electrical connection with each other, substantially as described.

4. In a relay for a diplex telegraph, the combination of two polar electro-magnets having two respective armatures capable of establishing electrical connection, a stationary electrical contact for one of said armatures, and two local sounders, substantially as described.

5. The combination, in a diplex relay, of two polar electro-magnets having armatures R R', capable of establishing electrical connection with each other, contact-stops c d e, electrical contact f, retracting - springs s s', and local sounders S S'.

GERRITT SMITH.
